Attorney

UNITED STATES PATENT OFFICE.

JOHN C. HENDERSON, OF NEW YORK, N. Y., ASSIGNOR TO THE LIBBEY-OWENS SHEET GLASS COMPANY, OF TOLEDO, OHIO, A CORPORATION OF OHIO.

HEATING MEANS FOR SHEET-GLASS APPARATUS.

Application filed January 13, 1927.. Serial No. 160,795.

The present invention relates to the production of sheet glass and has more particular reference to an improved type of sheet glass apparatus wherein a sheet is initially drawn in the vertical plane and then passed over a deflecting member into the horizontal plane.

An important object of the invention is to provide in sheet glass apparatus of the above character, means for heating the sheet while passing in the vertical plane whereby to facilitate the proper bending thereof into the horizontal plane.

Another object of the invention is to provide improved heating means of this nature, including means for passing an electrical current through said sheet.

A further object of the invention is to provide improved heating apparatus of this nature, wherein the electrical current may be caused to pass either vertically or transversely through said sheet.

A still further object of the invention is to provide improved heating means of the above character, including means for regulating the electrical current passing through said sheet, thereby permitting the temperature of said sheet to be accurately controlled.

Other objects and advantages of the invention will become more apparent during the course of the following description when taken in connection with the accompanying drawings.

In the drawings forming a part of this application and wherein like numerals are employed to designate like parts throughout the same,

Fig. 1 is a transverse vertical section through sheet glass apparatus showing the present improved heating means associated therewith, and

Fig. 2 is a longitudinal vertical section through the sheet glass apparatus showing a somewhat modified type of heating means.

Referring now to the drawings and more particularly to Fig. 1, the type of machine illustrated is that disclosed in the Colburn Patent No. 1,248,809 granted Dec. 4, 1917, wherein a sheet 5 is continuously drawn from a mass of molten glass 6 contained in a receptacle or so-called draw-pot 7, said pot being mounted upon stools arranged within

a heating chamber and adapted to be continuously replenished with molten glass from a suitable tank furnace.

55

The sheet 5 is drawn from the source 6 initially in the vertical plane and at a substantial distance from the said source is deflected over a so-called bending roll 8 into the horizontal plane where it passes over an idler roll 9 and draw-table 10 as shown in Fig. 2, after which it is carried through an annealing leir where it is gradually reduced to room temperature as is well known in the art. In order to maintain the sheet to width 60

65

there are provided at opposite edges of the sheet 5 closely adjacent the source 6, pairs of rollers 11 and 12 whose outer surfaces are preferably roughened or knurled and which rollers are carried upon the inner ends of 70 internally cooled shafts 13 and 14 respectively.

From the time the glass leaves the pool 6 until it reaches the bending roll 8, considerable heat has been dissipated so that the 75 sheet is relatively viscous and fairly well set. To overcome or prevent breakage or strains in the sheet as it passes over the bending roll 8, it is advisable to heat the sheet prior to the bending thereof and it is an aim of 80 the present invention to pass a sufficient amount of electrical current through the sheet during its vertical run necessary to heat the same, thereby facilitating the proper bending thereof.

85

In accordance with the present invention, a collar 15 is carried by one of the shafts 13 and engaging this collar is a stationary contacting member 16 to which is secured one end of a wire 17 leading to the transformer 90 18. A collar 19 is carried by the bending roll 8 at the same side of the sheet and is engaged by the stationary contact member 20 to which is secured one end of a wire 21 leading to the double knife switch 22, said 95 switch comprising the blade 23 pivoted between the contacts 24 and adapted to be swung to engage either the contacts 25 or 26. The wire 21 is secured to the contacts 25 while secured to the contacts 24 is one 100 end of a wire 27 leading to and being secured to the contacts 28 of the main control switch 29 which comprises the blade 30 pivoted between the contacts 31. Secured to

the contacts 31 is a wire 32 which leads to the transformer 18 and interposed in the length of this wire is the rheostat 33. The electrical current passing through the sheet 5 may be accurately controlled by proper regulation of this rheostat 33 as will be more clearly hereinafter apparent.

Carried by one of the shafts 14 at the opposite side of the sheet is a collar 35 engageable 10 by the stationary contact member 36 to which is secured one end of a wire 37, the opposite end thereof being secured to the contacts 26 of the double knife switch 22. A switch 38 is interposed between and connects the wire 15 37 and contact collar 15.

In operating a glass drawing machine with which the present improved heating means above described is associated, the glass is started in the usual manner and heated by 20 gas flames. After a temperature has been attained which is sufficient to cause the glass to become a conductor of electricity, the gas flame is extinguished and the electrical current turned on. With the switches 22 and 29 25 closed in the manner shown in Fig. 1 and the switch 38 also closed, it will be apparent that the electrical current when turned on, will pass from the transformer 18 into one edge of the sheet 6 through the shafts 13 and 30 knurled rollers 11 and that a portion of this current will also pass through the switch 38 and wire 37 and enter the opposite edge of said sheet through the shafts 14 and knurled rollers 12. The electrical current entering 35 the opposite edges of the sheet will pass upwardly therethrough as indicated by the vertical arrows in Fig. 1 in order to uniformly heat the said sheet throughout its mass. The heating of the sheet in this manner facilitates the proper bending thereof over the 40 roll 8 and also causes a very good glaze on the sheet without the ill effects of products of combustion as caused by gas fuel.

As the glass sheet passes over the bending 45 roll 8, the electrical current will be conducted therefrom by the said roll and will be caused to pass back through the switches 22 and 29 and rheostat 33 to the transformer 18. Upon proper regulation of the rheostat 33, the 50 amount of electrical current passing through the said sheet may be effectively controlled.

Should it be desired to pass the electrical current transversely instead of vertically through the sheet, the switch 38 is opened 55 and the blade 23 of switch 22 is thrown into engagement with the contacts 26, the switch 29 remaining in closed position as shown. The electrical current will then pass from the knurled rollers 11 transversely through 60 the sheet into and through the opposite knurled rollers 12 and will then pass through the wire 37 switches 22 and 29 back to the transformer. Thus, the knurled rollers 11 and 12 function respectively to conduct the 65 electrical current to and away from the sheet.

If desired, an auxiliary pair of sheet engaging rollers can be provided at each edge of the sheet to serve as the electrical conductors instead of using the usual rollers 11 and 12 which serve to maintain the sheet to width. 70

In Fig. 2 wherein has been shown a somewhat modified type of heating means, there are provided the electrodes 47 and 47' which depend into the mass of molten glass 6 in draw pot 7 at the opposite sides of sheet 5. 75 These electrodes can also be positioned at the opposite edges of the sheet as well as at the opposite sides thereof if desired. Leading from the electrode 47 is a wire 39 secured to the contacts 48 of the control switch 49, while leading from the electrode 47' is a wire 40 also secured at its opposite end to the contacts 48. The switch 49 comprises a blade 50 pivoted between the said contacts 48 and movable into and out of engagement with the contacts 51. Secured to the contacts 51 is a wire 52 leading to the transformer 53 and this transformer is connected by means of a wire 54 with the bending roll 8. Thus, after the molten glass 6 and sheet 5 have attained a temperature sufficient to render them a conductor of electricity, the switch 49 is closed and the electrical current turned on whereupon the said current will pass from the transformer through the wire 52 to the switch 49 and thence through the wires 39 and 40 to the electrodes 47 and 47'. The electrical current will then pass through the molten glass 6 into and through the sheet heating the same and the said current will be subsequently conducted away from the sheet by the bending roll 8 and passed back to the transformer 53. A suitable rheostat may be also interposed in this circuit if preferred in order to regulate the amount of 90 current passing through the sheet. 95

It will be found that by use of this means of heating that the temperature of the glass will automatically adjust itself. That is, if the machine is drawing relatively thick 110 glass, the current will have a longer period in which to heat and when drawing relatively thin glass and the machine is moving at a higher rate of speed, the current will have a shorter period of time in which to heat. 115

It is to be understood that the form of the invention herewith shown and described is to be taken as the preferred embodiment of the same, and that various changes in the 120 shape, size and arrangement of parts may be resorted to without departing from the spirit of the invention or the scope of the subjoined claims.

I claim:

1. In sheet glass apparatus, means for drawing a sheet from a mass of molten glass, and means for passing an electrical current through said sheet whereby to heat the same. 130
2. In sheet glass apparatus, means for

- drawing a sheet vertically from a mass of molten glass, and means for passing an electrical current vertically through said sheet whereby to heat the same.
- 5 3. In sheet glass apparatus, means for drawing a sheet from a mass of molten glass, and means for passing an electrical current transversely through said sheet whereby to heat the same.
- 10 4. In sheet glass apparatus, means for drawing a sheet from a mass of molten glass, means for deflecting said sheet from one plane to another, and means for passing an electrical current through said sheet whereby to heat the same prior to the deflecting thereof.
- 15 5. In sheet glass apparatus, means for drawing a sheet from a mass of molten glass, means for deflecting said sheet from one plane to another, and means for passing an electrical current transversely through said sheet whereby to heat the same prior to the deflecting thereof.
- 20 6. In sheet glass apparatus, means for drawing a sheet vertically from a mass of molten glass, means for deflecting said sheet from the vertical into the horizontal plane, and means for passing an electrical current vertically through said sheet during its vertical run to heat the same prior to the deflecting thereof.
- 25 7. In sheet glass apparatus, means for drawing a sheet vertically from a mass of molten glass, means for deflecting said sheet from the vertical into the horizontal plane, and electrical means for heating the glass during its vertical run to soften the same throughout its mass prior to the deflecting thereof.
- 30 8. In sheet glass apparatus, means for drawing a sheet from a mass of molten glass, means for passing an electrical current through said sheet whereby to heat the same, and means for deflecting said sheet from one plane to another and for conducting the electrical current away from said sheet.
- 35 9. In sheet glass apparatus, means for drawing a sheet vertically from a mass of molten glass, means for passing an electrical current through said sheet whereby to heat the same, and a rotatable bending member for deflecting said sheet from the vertical into the horizontal plane and for conducting the electrical current away from said sheet.
- 40 55 10. In sheet glass apparatus, means for drawing a sheet from a mass of molten glass, means for passing an electrical current through said sheet whereby to heat the same, and a rotatable electrical conducting member for deflecting said sheet from one plane to another.
- 45 11. In sheet glass apparatus, means for drawing a sheet from a mass of molten glass, means for deflecting said sheet from one plane to another, and sheet edge engaging
- means for causing an electrical current to pass through said sheet whereby to soften the same.
- 50 12. In sheet glass apparatus, means for drawing a sheet from a mass of molten glass, means for deflecting said sheet from one plane to another, and width maintaining means engaging said sheet for causing an electrical current to pass therethrough to heat the same.
- 55 13. In sheet glass apparatus, means for drawing a sheet vertically from a mass of molten glass, a rotatable bending member for deflecting said sheet from the vertical into the horizontal plane, and rotatable width maintaining members engaging said sheet and adapted to cause an electrical current to be passed through said sheet to heat the same.
- 60 14. In sheet glass apparatus, means for drawing a sheet vertically from a mass of molten glass, and members engaging the opposite edges of the sheet and adapted to conduct an electrical current to and away from said sheet.
- 65 15. In sheet glass apparatus, means for drawing a sheet vertically from a mass of molten glass, and members engaging the opposite edges of the sheet and adapted to cause an electrical current to be passed transversely therethrough.
- 70 16. In sheet glass apparatus, means for drawing a sheet vertically from a mass of molten glass, and width maintaining members engaging said sheet at opposite edges thereof and adapted to cause an electrical current to be passed transversely therethrough.
- 75 17. In sheet glass apparatus, means for drawing a sheet vertically from a mass of molten glass, and width maintaining members engaging said sheet at opposite edges thereof for conducting an electrical current to and away from said sheet.
- 80 18. In sheet glass apparatus, means for drawing a sheet from a mass of molten glass, means for deflecting said sheet from one plane to another, and means engaging the edges of said sheet, said edge engaging means and deflecting means acting respectively to conduct an electrical current to and away from said sheet.
- 85 19. In sheet glass apparatus, means for drawing a sheet vertically from a mass of molten glass, a rotatable bending member for deflecting said sheet from the vertical into the horizontal plane, and rotatable members engaging the edges of said sheet, said edge engaging members and bending member acting respectively to conduct an electrical current to and away from said sheet.
- 90 20. In sheet glass apparatus, means for drawing a sheet from a mass of molten glass, means for passing an electrical current vertically through said sheet to heat the same.

same, and means operable to change the path of travel of the electrical current to cause it to pass transversely through said sheet.

21. In sheet glass apparatus, means for drawing a sheet from a mass of molten glass, a bending member for deflecting said sheet from one plane to another, means for causing an electrical current to pass transversely through said sheet, and means operable to cause the electrical current to change its path of travel and pass vertically through said sheet and longitudinally through said bending member.

22. In sheet glass apparatus, means for drawing a sheet from a mass of molten glass, a bending member for deflecting the sheet from one plane to another, means for causing the electrical current to pass vertically through said sheet and longitudinally through said member, and means operable to cause the electrical current to change its path of travel and pass transversely through said sheet only.

23. In sheet glass apparatus, means for drawing a sheet from a mass of molten glass,

a bending member for deflecting the sheet from one plane to another, and means for causing an electrical current to be introduced into the opposite edges of said sheet.

24. In sheet glass apparatus, means for drawing a sheet from a mass of molten glass, a bending member for deflecting the sheet from one plane to another, and means for causing an electrical current to pass into the sheet at one edge thereof and pass out of said sheet at its opposite edge.

25. In sheet glass apparatus, a receptacle adapted to contain a mass of molten glass, means for drawing a sheet from said molten glass, electrodes depending into the molten glass at opposite sides of the sheet, and being connected in series, and means for passing an electrical current through said electrodes, molten glass and sheet to heat said sheet.

Signed at Toledo, in the county of Lucas and State of Ohio, this 4th day of January, 1927.

JOHN C. HENDERSON.
